MACHINE WITH PRESSURE MEDIUM DRIVE
FOR RIVETING PERFORATED WORK-
PIECES

Karl Weinhold, Frankfort-on-the-Main, Germany, assignor to Frankfurter Maschinenbau Aktiengesellschaft, vorm. Pokorny & Wittekind, Frankfort-on-the-Main

Application August 29, 1939, Serial No. 292,466
In Germany September 6, 1938

4 Claims. (Cl. 78—48)

The known machines for automatically punching and riveting workpieces are suitable practically only where it is a question of continual working of a relatively large number of similar workpieces with numerous rivets and uniform rivet distribution. However, particularly in the aeroplane manufacture, many constructional parts have to be worked, which are not similar and have varying rivet distribution.

For riveting these constructional parts the workpieces were hitherto only held together at certain places by attaching screws, the rivet holes were drilled with simple drilling machines and the riveting carried out with the aid of riveting presses or riveting hammers. This requires a considerable amount of work and time, as it is necessary to secure the rivet in very close spacing, in order to obtain a good plate closing and also every rivet must be introduced by hand into its rivet hole so that the set head sits well. This work requires a considerable amount of time in the case of bulky workpieces. Moreover, two well-trained workers are necessary for riveting by means of a riveting hammer, one of which workers inserts and clinches the rivet and the other attends to the dolly.

These objections are overcome according to the invention in that the snap serving for forming the rivet tail and a resilient centering pin longitudinally slidably therein and with which the workpieces are brought into contact are mounted in the work table and that above the workpiece a plate closer, a rivet driving die slidably mounted therein, and an automatic rivet feeding device are arranged and that, by adjusting a shut-off element, the pressure medium is first fed to a piston controlling the plate closer with the result that the plate closer containing the rivet is lowered on to the workpiece. By further adjustment of the shutting-off element pressure medium is fed to the piston controlling the rivet driving die with the result that the rivet is driven in and forces back the resilient centering pin, and that, after the driving in operation, the pressure medium feed to the piston of the press driving the snap becomes free for the formation of the tail, the rivet driving-in die remaining on the set head as a dolly. In this construction of the machine the worker only has to bring the workpieces, for example plates to be riveted, into engagement with the centering pin and to actuate the shut-off element with the aid of a lever. The operations necessary for closing the plates, introducing the rivets, holding up and for the formation of the tail then take place automatic-

ally. Even in the case of bulky workpieces and those with varying rivet distribution, the expenditure of work and time necessary for the joining is considerably less than hitherto, one operation being sufficient. The riveting of the perforated workpieces is also more simple and clear.

To be certain that the formation of the tail is only commenced after the rivet driving die serving as a dolly bears against the set head of the rivet, an aperture is arranged, according to the invention, in the cylinder of the pressure piston serving for operating the rivet driving die, this aperture being liberated after the rivet has been set and effects the feed of pressure medium to the pressure piston operating the snap.

In the case of simple passage arrangement the proper feeding of the rivets can be ensured in that an aperture is provided in the cylinder of the piston serving for operating the rivet driving die, this aperture being opened at the end of the stroke and serves for effecting the drive of the rivet feeding device.

To facilitate the attendance of the machine by the fact that, after the riveting operation, all the tools are returned automatically into their initial positions merely by the releasing of the lever serving for adjusting the shut-off element, all pressure pistons are, according to the invention, acted upon by return springs and the shut-off element is constructed as a piston slide valve under the action of a return spring, all pressure medium cylinders being in communication with the atmosphere when this shut-off element is in its initial position. As the control of the pressure medium feed to the pressure piston operating the snap and to the pressure piston operating the rivet feeding device is effected by the pressure piston serving for operating the rivet driving die, the same passages at the return of the shut-off element into its initial position, can serve for bringing these three pistons into communication with the atmosphere by means of common passages.

An embodiment of the invention is illustrated by way of example in the accompanying drawings, in which:

Fig. 1 shows a portion of the machine in longitudinal section,

Fig. 2 shows a portion of Fig. 1 on a larger scale,

Fig. 3 shows on a smaller scale the portion of the machine illustrated in Fig. 1 in a different operating position,

Fig. 4 is a similar view to Fig. 3 showing the

machine portion in yet another operating position.

Fig. 5 is a similar view to Fig. 1 but in a different operating position.

5 Fig. 6 is a side elevation of Fig. 3, some parts being shown in section.

Fig. 7 is a plan view of Fig. 6 partly in section.

Fig. 8 is a section on line VIII—VIII of Fig. 7.

10 Fig. 9 shows a portion of Fig. 6 in side elevation and on a larger scale.

Fig. 10 is a top plan view of Fig. 9.

Fig. 11 shows the slide valve in section and in another operating position.

15 Fig. 12 is a top plan view of Fig. 11.

The plate closer, the rivet driving-in die, the rivet feeding device and the shut-off element are arranged in the upper part of the bowl 1 in the machine head 2 and by means of this shut-off element the pressure pistons of these devices are subjected to the action of compressed air which is fed through the conduit 3. The work table, the centering pin and the pneumatic press for the forming of the rivet tail are accommodated in the lower part 4 of the bowl 1.

20 The plate closer which will be hereinafter described has a sleeve 5 which is longitudinally shiftable in the head 2 and rigidly connected by means of a bolt 6 with a pneumatic piston 7 which can reciprocate in a pneumatic cylinder 8 and is under the action of a spring 9. A piston slide valve 10 is mounted in a sleeve 11 in the head 2 at the side of the pneumatic piston 7. The sleeve 11 has at its lower end an aperture 12 through which a rod 13 extends. A lever 14 keyed on a shaft 15 bears against this rod 13. A handle 16 (Fig. 6) is also keyed on the shaft 15.

30 The piston slide valve 10 is acted upon by a spring 17 which bears against the bottom of the sleeve 11 and tends to bring the valve into the position shown in Fig. 1 in which the compressed air feed conduit 3 is shut-off from the interior of the cylinder 8. The piston slide valve at the same time shuts off the feed conduit 18 leading into the annular space 19 of the piston slide valve from the aperture 20 which communicates with the interior of the cylinder 8 through a passage 21.

35 A guide piece 23 of the rivet driving die 22 is longitudinally shiftable in the sleeve 5 of the plate closer and a second guide piece 24 is connected to the guide piece 23. A toggle lever consisting of three members 25, 26, 27 mounted on a common bolt 28 is connected with the guide piece 24. The member 26 of the toggle lever is oscillatable about the bolt 28 fixed in the head 2, the member 25 is oscillatable about a bolt 30 journalled in the guide piece 24 and the member 27 is oscillatable about a bolt 31 mounted in a pressure piston 32. This pressure piston is reciprocatable in a cylinder 33 and under the action of a spring 34. A port 35 in the lower portion of the cylinder 33 communicates by a passage 36 with a port 37 in the guide sleeve of the piston slide valve 10 so that, when the piston slide valve is in the position shown in Fig. 1 the compressed air conduit 3 is shut-off from the port 37.

40 The rivet feeding device operates like a lock to 70 which the rivets are fed from a semi-spherical dish 38 into which a rivet gripper 39 can be swung and out of which the gripper can be swung so that the rivets are brought into alignment with the mouth of the passage 40 in the guide rail 41 (Fig. 6).

The rivet gripper, which has a slot 42 into which the rivets 43 drop, is fixed on a shaft 44 arranged at the inlet of the passage 40 in the guide rail 41 and carrying a pinion 45 which meshes with a rack 46 on a pressure piston 47 reciprocable in a cylinder 48 (Fig. 8). This piston is acted upon by a spring 49 and can be moved by hand with the aid of a knob 50. The cylinder 33 accommodating the pressure piston 32 has an aperture 51 (Fig. 1) connected by a hose 52 (Fig. 7) to the cylinder 48.

45 The dish 38 and the rivet gripper 39 are arranged in a housing 53 which is fixed on the machine head 2 by means of a support 54. The guide rail 41 is secured on this housing 53 by means of a support 55.

50 A slide 56 is fitted in the guide rail 41 (Figs. 9 to 12), this slide being acted upon by a spring 57 on the one hand and controlled by an abutment 58 on the plate closer on the other hand (Fig. 1). This abutment 58 is arranged on an extension 59 connected with the sleeve 5. At the side of the slide 56 a shaft 62 is journalled in bearings 60, 61 on the rail 41. A lever 63 is keyed on one end of this shaft and cooperates with the abutment 58. A lever 64 is keyed on the other end of shaft 62 and bears against the slide 56. The lever 63 is acted upon by a blade spring 65 fixed on the rail 41.

55 The slide 56 consisting of the two parts 56a and 56b has an aperture 66 corresponding in width to the width of the passage 40. An abutment piece 56c is fixed on the slide proper 56 and carries a handle 68. The slide 56 is guided on the guide rail 41 which for this purpose has two straps 56f and 56g. The rivets 43 with their shanks in the passage 40 and their heads in an aperture 67 can come between the straps 56f and 56g of the rail 41. The aperture 66 is oblique 40 (Figs. 9 to 12) so that, when the slide 56 (Fig. 10) is in one position, one rivet 43 comes into the position ready for use and, when the slide is in its other position (Fig. 12), this rivet can move on in the passage 40 whereas the opposite rivet is 45 blocked at the entrance to the aperture 66.

60 A movable part (Fig. 1) cooperates with the stationary part 41 of the rivet feeding device and is mounted in an extension piece 58 of the plate closer. This movable part has a passage 69 whose cross-section corresponds to that of the passage 40. This passage 69 extends to a bore 70 for the rivet driving-in die 22 in the extension piece 59. The lower end of the plate closer 5 is formed by a carrier 71 for two gripper jaws 72 which are each oscillatable about an axle 73 formed on the carrier 71 and held together by a rubber band 74. The carrier 71 has a bore 75 as passage for the rivet driving-in die 22. The carrier 71 bears with its lower end 76 against the 65 plates 77, 78 to be riveted together.

65 The riveting press arranged in the lower part 4 of bowl 1 is a toggle lever press, the toggle lever consisting of the members 79, 80, 81. The member 79 is oscillatable at one end about a bolt 82 and hingedly connected to a piston 83 which reciprocates in a cylinder 84; the member 79 is hingedly connected at its other end with the member 80 by a bolt 85. The member 80 is oscillatable about a bolt 86 mounted in a 70 housing 87. The member 81 is oscillatable at one end about a bolt 88 eccentric to bolt 86 and is connected at its other end to a guide element 89 for the snap 90 by a bolt 91. This guide element 89 is longitudinally shiftable in the hous- 75

ing 87. The housing 87 is held on the cylinder housing 84 by two pins 92 and is screw threaded on its upper end for the vertical adjustment of the rivet press with the aid of a nut 93.

5 The cylinder 84 is connected by a hose conduit 94 to a nozzle 95 leading to an aperture 96 in the cylinder 33 of the pressure piston 32. This aperture 96 is so arranged that it is liberated at the end of the stroke of the pressure piston. The piston 83 is under the influence of a return spring 97.

10 The snap 91 is guided in a guide piece 98 forming the work table. This guide piece 98 is fitted in the housing 87 and is vertically adjustable by means of a nut 99. The snap 91 has on its lower end a widened portion 100 fitted in a recess in the guide element 98. The widened portion 100 is hollow and accommodates the head 101 of a centering pin 102 which is guided in the snap 91. A spring 103 bears against the head 101, so that the centering pin 102 is yieldably mounted. The spring 103 tends to bring the centering pin 102 into a position, in which it projects beyond the surface of the work table 15 98. The end face of the centering pin 102 can be accurately adjusted in the plane of the uppermost surface of the snap 91 with the aid of an abutment screw 104, so that no step is formed in the flat head during the upsetting operation.

20 30 The riveting machine operates in the following manner:

Before the riveting is commenced, the plates 17, 18 provided with holes 105 are placed on the work table 98, one hole being placed on the centering pin 102. The parts of the machine then assume the position shown in Fig. 1, in which the pressure pistons 7, 32 and 83 are in one of their extreme positions under the action of the springs acting upon them and the piston slide valve 10 is in a position in which the cylinders of these pressure pistons communicate with the atmosphere.

25 40 The rivets 43 are first placed in the dish 38 of the rivet feeding device and by pushing inwards the knob 50 the rivet gripper 39 is swung into its upper position indicated in dot-dash lines in Fig. 6, so that the rivets drop into the guide rail 41 and get in front of the slide 56. This slide is moved by means of the handle 68 so that the aperture 66 of the slide first comes into the position shown in Fig. 10, whereupon the slide is shifted in the opposite direction, into the position shown in Fig. 12 with the result that a rivet is separated from the row of rivets, shifts on 45 50 55 60 65 70 75 in the guide rail 41 and enters the stationary passage part 69 where it rests against the rivet driving-in die 22 (Fig. 1).

If the operator then depresses the lever 16, the piston slide valve 10 assumes the position shown 60 in Fig. 3. During this movement the apertures 20 and 37 are first shut-off from the atmosphere and the aperture 20 is brought into communication with the annular space 19 of the piston slide valve and consequently with the compressed air feed conduit 3. The compressed air enters into the cylinder 8 through the conduit 21, forces the piston 7 forward, thereby compressing the spring 9 and the piston shifts the sleeve 5 of the plate closer until the face 76 bears against the plate 70 75 80 85 90 95 100 105 110 115 120 125 130 135 140 145 150 155 160 165 170 175 180 185 190 195 200 205 210 215 220 225 230 235 240 245 250 255 260 265 270 275 280 10020 10025 10030 10035 10040 10045 10050 10055 10060 10065 10070 10075 10080 10085 10090 10095 10100 10105 10110 10115 10120 10125 10130 10135 10140 10145 10150 10155 10160 10165 10170 10175 10180 10185 10190 10195 10200 10205 10210 10215 10220 10225 10230 10235 10240 10245 10250 10255 10260 10265 10270 10275 10280 10285 10290 10295 10300 10305 10310 10315 10320 10325 10330 10335 10340 10345 10350 10355 10360 10365 10370 10375 10380 10385 10390 10395 10400 10405 10410 104

air can also pass out of the cylinder 48 through the conduit 52 and the aperture 51 into the cylinder 33 and consequently into the atmosphere. The piston 47 therefore returns into its initial position under the action of its return spring 49 with the result that the rivet gripper 39 is raised in clockwise direction into the position indicated in dot-dash lines in Fig. 6 so that rivets drop into the guide rail 41.

- 10 During the upward movement of the plate closer 5 the abutment 58 comes into contact with the lever 63 of the controlling mechanism of the rivet feeding device and thus brings the slide 56 out of the position ready for operation shown in 15 Fig. 10 into the position shown in Fig. 12 in which a rivet 43 is separated and can enter the movable part 69 of the guide rail provided on the plate closer 5.

Consequently, the operator need only bring the 20 perforated plates 71, 78 into engagement with the centering pin 102, depress the lever 16 and then release it. All operations necessary for the riveting then take place automatically in the requisite succession, that is the plate closing, the 25 introduction of the rivet in the rivet hole, the upsetting of the rivet which is at the same time held by the dolly, the bringing of the rivet into its position ready for use in the rivet feeding device, the feeding of the following rivets and the return movement of all the parts into their 30 initial position.

The machine is also suitable for countersunk pull through riveting. The countersinking in the plates 71, 78 is effected by the rivet driving-in die 22. The centering pin 102, owing to its resilient mounting, retracts into the snap 91 so far that its end face is in the same plane as the upper edge of the snap.

I claim:

- 40 1. A machine with pressure medium drive for riveting perforated plates especially those with varying rivet spacing, comprising in combination

a work table, a snap mounted in said work table and adapted to form the tail, a resiliently mounted centering pin slidable in said snap and adapted to engage the workpiece, a plate closer arranged above the workpiece, a rivet driving-in die shiftably mounted in said plate closer, a piston controlling said plate closer, a piston controlling said rivet driving-in die, a driving press for said snap and comprising an operating piston, and a shut-off element adapted first to feed 10 the pressure medium to the piston controlling said plate closer to lower on to the workpiece the plate closer containing the rivet, then to feed the pressure medium to the piston controlling the rivet driving-in die to drive the rivet into the 15 workpiece and force back the resiliently mounted centering piece, and finally to the piston of the press actuating the snap to form the rivet tail, the rivet driving-in die remaining on the set head 20 as a dolly.

2. In a machine as specified in claim 1, a cylinder accommodating the piston controlling the rivet driving-in die, and having an aperture adapted to be opened after the driving-in of the rivet and to supply pressure medium to the piston controlling the snap.

3. In a machine as specified in claim 1, a cylinder accommodating the piston controlling the rivet driving-in die and having an aperture adapted to be opened when said piston reaches 30 the end of its stroke and to supply pressure medium to the rivet feeding device.

4. In a machine as specified in claim 1, cylinders each accommodating one of said pistons, return springs one on each of said pistons, the 35 shut-off element constructed as piston slide valve, and a return spring acting on said piston slide valve, said shut-off element adapted in its initial position to connect all of said cylinders with the atmosphere.

40 KARL WEINHOLD.
